SHAKEOUT DEVICE FOR FOUNDRY MOLDS

Charles M. Young, Jr., Chicago, Ill., assignor to Link-Belt Company, a corporation of Illinois

Application December 1, 1954, Serial No. 472,387

20 Claims. (Cl. 22—95.7)

This invention relates to new and useful improvements in foundry equipment, and deals more particularly with a fully automatic machine for removing the sand and castings from mold flasks having permanent grid bars in the drags or bottom portions thereof.

In a conventional foundry system, the sand molds are formed in flasks that are open at their upper and lower ends. If the flasks and mold are small, irregularities in the sides of the flask, or the mere adhesion of the sand mold to the flask, will prevent the sand and casting from falling out of the flask during transportation and handling. For large sized molds and flasks, however, it is a usual practice to provide permanent grid bars in the drag sections of the flasks to support the molds until after the castings are poured and to keep the molds intact while the castings cool and the flasks are transported to the shakeout location.

Since the grid bars in the bottom of the flask will prevent the sand and casting from being shaken out through the bottom of an upright flask, it is necessary that the flask be inverted before the shakeout operation can be performed. For fully mechanized foundries, the inversion or rollover of a poured mold and flask, and the shaking out of the sand and casting, usually are accomplished with the assistance of manually operated or controlled devices. With the presently developing use of fully automatic foundry systems, however, the need for a simple and efficient machine to automatically carry out the above described rollover and shakeout operations has become increasingly great.

It is the primary object of this invention to provide a fully automatic machine for removing the sand and castings from flasks having permanent grid bars in the bottom portions, or drags, thereof.

A further important object of the invention is to provide a fully automatic machine for removing poured and cooled mold flasks from a continuously moving mold conveyor, inverting the flasks and shaking out the sand and castings, and finally transferring the empty flasks to a conveyor mechanism which will transport them away from the machine to a location for reuse.

A further important object of the invention is to provide a machine which will operate entirely automatically, and in proper timed relation to the continuous travel of a flask type mold conveyor, to remove the flasks and their molds from the conveyor, as they reach the location of the machine, and transfer them to a rollover mechanism in which they are first clamped, then inverted and finally unclamped; to move the inverted flasks to a shakeout device in which the sand and castings are discharged; and to finally transfer the empty flasks to a further conveyor mechanism which will remove them from the location of the machine.

Still another important object of the invention is to provide an automatic machine of the above mentioned type in which the transferring of a flask from the mold conveyor to the rollover device will not take place if, for any reason, the previously transferred flask remains

in the rollover device beyond its allotted time, and in which the mold conveyor will be stopped if a flask carried thereby is moved beyond the point at which it should have been transferred to the rollover device.

Another important object of the invention is the provision of an automatic machine of the above mentioned type in which the rollover device will not operate to invert a flask prior to the proper clamping of the flask therein, and the means for moving an inverted flask from the rollover device will not operate prior to the unclamping of the flask that is positioned in said device.

A further important object of the invention is to provide a mechanism for receiving mold flasks which, when a flask is introduced thereto, will automatically clamp and invert the flask and will thereafter release the flask for removal from the mechanism.

Another important object of the invention is to provide an inverting mechanism which will be actuated automatically by the introduction of a flask thereto to sequentially clamp, invert and release the flask, and in which the outer face of the cope of the inverted flask will be automatically located at the same level as the bottom face of its drag occupied at the time the flask was introduced to the inverting mechanism.

Other objects and advantages of the invention will be apparent during the course of the following description.

In the accompanying drawings forming a part of this specification, and in which like reference characters are employed to designate like parts throughout the same,

Figure 1 is a top plan view of a fully automatic mold and flask rollover and shakeout machine embodying this invention,

Figure 23 is a wiring diagram of the electrical circuits connecting the various control elements, and

Figure 24 is a time cycle chart illustrating the sequence and direction of movement of the fluid motors employed in the illustrated machine.

In the drawings, wherein for the purpose of illustration is shown the preferred embodiment of this invention, and first particularly referring to Figs. 1 to 3, inclusive, reference character 25 designates a conventional type of continuous mold conveyor made up of uniformly spaced, mold supporting trays 26. Each tray 26 is provided with a switch operating lug 27 and the lugs of all of the trays extend laterally outwardly from corresponding sides thereof. As illustrated in Figs. 1 and 3, flasks 28, containing the sand molds and castings, are supported individually on the trays 26 and the cope 29 and drag 31 of each flask 28 are provided with longitudinal spacer plates 32 at the opposite ends thereof and with laterally projecting guide bars 33 at each end portion of their opposite sides.

Arranged at right angles to one side of the path of travel of the conveyor 25 is a transfer device A, the actuating element of which is movable across the path of travel of the conveyor to push a poured mold flask 28 off of its supporting tray 26 onto a series of rolls 34 at the opposite side of the conveyor. The rolls 34 are arranged between the conveyor and a rollover device B to support the poured flasks 28 for movement from the conveyor to the rollover device.

After entering the rollover device B, each flask 28, with its sand and casting, is inverted and subsequently engaged by a transfer device C for longitudinal movement from the rollover device onto a shakeout device D where the sand and casting are discharged from the flask. As each flask 28 is moved longitudinally from the rollover device B onto the shakeout device D, the preceding discharged flask is ejected from the shakeout device by engagement between the spacer plates 32 of the two flasks. Upon leaving the shakeout device D, each flask 28 is moved onto a table of rolls 35 from which it is discharged by a transfer device E onto a gravity type roller conveyor 36 for return to a point of reuse.

Positioned beneath the shakeout device D is a conventional screen 37 for separating the mold sand and castings and a chute or conveyor 38 is positioned at the discharge end of the screen for transporting the castings to any desired location.

Referring now to Figs. 1, 3 and 10 for a detail description of the transfer device A, it will be noted that it is positioned on a support 39 which is formed of suitably reinforced structural members. Extending longitudinally between the opposite ends of the support 39 are a pair of laterally spaced angle irons 41, the opposite end portions of which are provided with additional angle members 42 arranged in back-to-back relationship with the members 41. Resting on the aligned top flanges of the angle irons 41 and members 42 at each end of the support 39 are two spaced support plates 43 upon which are securely mounted the opposite end portions of a double acting fluid motor 44. The plates 43 are supported on the angle irons 41 for longitudinal adjustment by bolts 45 which pass through holes in the angle irons and elongated slots 46 in the plates. Projecting downwardly from the plate 43 at the outer end of the support 39 is an adjusting lug 47 which is threadedly connected to a shaft 48 rotatably mounted on the support 39 and having a handwheel 49 mounted thereon. Rotation of the shaft 48 effects longitudinal move-

ment of the plates 43 and the fluid motor 44 and subsequent tightening of the bolts 45 fixes the position of the motor. The plates 43 at opposite ends of the support 39 are provided with vertically extending switch mounting brackets 50 and 51 at corresponding sides of the plates. It will be noted that the fluid motor 44 is supported by the plates 43 in horizontal alignment with the path of travel of the flasks 28 on the conveyor 25.

The piston rod 52 of the fluid motor 44 is provided with an expandable and contractible bellows type protective cover 53 to prevent abrasion of the rod by dust, or the like, and the outer end portion of the rod is pivotally connected to a pusher plate 54 that is suspended from two laterally spaced and longitudinally extending guide members 55. The guide members 55 have outwardly extending flanges confined between the spaced flanges of angle members 56 at each side of the support 39. A bearing plate 57 and guide block 58 are arranged between the vertically spaced angle members 56 at each side of the support 39 to accurately control the movement of the guide members 55. The guide member 55 at the side of the support 39 adjacent the switch mounting brackets 50 and 51 is provided with a switch actuating cam 59 which moves along the support as the piston rod 52 of the fluid motor 44 is extended and retracted.

A limit switch A1 is secured to the switch mounting bracket 50 at the outer end of the support 39 and limit switches A2 and A3 are mounted on the bracket 51 at the inner end of the support with each of the three switches having its actuating arm in alignment with the path of travel of the switch actuating cam 59. The operation of the limit switches A1, A2 and A3 will be later described.

As illustrated in Figs. 1 to 3, inclusive, the rollover device B is mounted on a suitable supporting structure designated in its entirety by the reference character 61. The rollover device B is of drum-like shape and is supported for rotation about its axis by rollers 62 that are mounted on the supporting structure 61 by means of bearings 63. Two spaced rollers 62 are arranged at each end portion of the rollover device B so that the device is supported with its axis substantially in alignment with the mold flask 28 opposite the transfer device A.

Referring now to Figs. 4 to 9, inclusive, for a detail description of the rollover device B, it will be noted that the end of the device adjacent the rolls 34 is formed of a single, substantially annular end plate 64 having a substantially rectangular, centrally located opening 65 therein. Guide flanges 66 are arranged at each side of the opening 65 and extend outwardly therefrom so that the lowermost guide flange 66 will lie adjacent the rolls 34 after each 180° rotation of the rollover device B. The lowermost flange 66, therefore, guides a mold flask 28 as it is moved from the conveyor 25 across the rolls 34 and into the rollover device B by the transfer device A. An axially directed tire 67 is mounted on the end plate 64 adjacent its periphery for engagement with the rollers 62 at the flask receiving end of the rollover device B.

The opposite end of the rollover device B is formed with an inner plate 68 and an outer plate 69 having a circular tire 71 positioned therebetween slightly inwardly of their peripheries, said plates and tire being connected to each other by circumferentially spaced bolts 72. The tire 71 engages the supporting rollers 62 associated with this end of the rollover device B and the edges of the plates 68 and 69 serve to prevent axial movement of the device on its supporting rollers.

Extending between and connecting the plate 64 at the flask receiving end and the plates 68 and 69 at the opposite end of the rollover device B are four pairs of right angularly arranged plates 73 and 74, best shown in Fig. 6, which are provided with stiffening webs 75 and are arranged to provide rectangular openings at four circumferentially spaced locations in the periphery of the rollover device. The planes of the four openings formed by the

plates 73 and 74 are in alignment with the four sides of the opening 65 in the end plate 64 so that the opposed openings between the plates 73 are alternately positioned adjacent the shakeout device B and the opposed openings between the plates 74 are alternately positioned in alignment with the rollers 34 by each 180° rotation of the rollover device.

Positioned in each of the two opposed openings formed between plates 74 is a mold flask clamping plate 76 which is limited as to its extent of radially outward movement by blocks 77 that are mounted at spaced points around the openings. The outer face of each plate 76 has mounted thereon two longitudinally extending guide members 78 which are connected by cross members 79 having positioned longitudinally therebetween a mounting lug 81, see Figs. 4, 6 and 8. The mounting lug 81 of each plate 76 is located at the longitudinal centerline of the plate and the guide members 78 of the two plates are offset laterally in opposite directions so that vertically opposed pairs of guides 78 are laterally offset relative to each other.

Each mounting lug 81 has pivotally connected thereto a link 82, the outer end of which is pivotally connected to the inner end of a lever 83 which is pivotally mounted between spaced bracket plates 84 at the end of the rollover device B opposite the flask receiving end, see Fig. 4. Each of the bracket plates 84 is formed with a lug 85 projecting inwardly to support the adjacent edge of the associated clamping plate 76 to limit the radial outward movement of this portion of the plate. The outer ends of the two levers 83 are connected, respectively, to the piston rod 86 and cylinder 87 of a double acting fluid motor 88 so that relative extension of the operating rod and cylinder will cause the clamping plates 76 to move toward each other and relative contraction of the piston rod and cylinder will cause the plates to move away from each other. It will also be noted that for any given relative position of the piston rod 86 and cylinder 87, the fluid motor 88 may move as a unit in either vertical direction while the two clamping plates 76 also will move as a unit, or jointly, at the same time as the motor 88 but in the opposite vertical direction. The extent of vertical movement of the plates as a unit in either vertical direction will be limited by one or the other of the two sets of blocks 77.

At the end of the rollover device B opposite its flask entering end, see Figs. 6, 7 and 8, the guide members 78 on the outer sides of the plates 76 extend into guide slots 89 that are formed in the inner end plate 68. Welded, or otherwise suitably connected, to the end portion of each guide member 78 within its associated slot 89 is a guide bar 91 which extends along the side of the slot between the two end plates 68 and 69 and is provided with a shoe 92. Because of the laterally offset relationship of the vertically opposed guide members 78, the shoes 92 associated therewith are laterally offset to provide a space between the opposed faces of their overlapped end portions. Mounted on the outer plate 69 and extending inwardly into the space between the opposed faces of the overlapped end portions of the shoes 92 is a guide bar 93 which will maintain proper spacing between the shoes and will confine the guide bars 91 and shoes 92 for movements in parallel paths so that the clamping plates 76 will be maintained in substantially parallel relationship.

Mounted on the outer face of each camping plate 76 and extending outwardly therefrom, see Figs. 3, 4, 6 and 7, is a bracket 94 having a follower 95 mounted on its outermost portion. Two cam plates 96 are mounted above and on opposite sides of the rollover device B in the paths of movement of the followers 95 for a purpose that will later be described.

Mounted on the outer face of the plate 69 in spaced relationship thereto, see Figs. 2 to 5 and 7, is a toothed gear segment 97 that is arcuate in form and extends through slightly more than one-half the circumference of the plate 69. A driving pinion 98 is mounted on a coun-

tershaft 99, supported by bearings 101, for driving engagement with the gear segment 97 to effect rotation of the rollover device B. Driven pinion 102 is also mounted on the shaft 99 for rotation therewith and a rack 103 is slidably supported for longitudinal movement in meshing engagement with the pinion 102. As best illustrated in Figs. 2 to 5 and 9, the rack 103 is mounted on a plate 104 the opposite side edges of which are positioned between two pairs of guide flanges 105 and are supported on the lower flanges by wear plates 106. Mounted above the supporting flanges 105 is a double acting fluid motor 107, the piston rod 108 of which is connected at its outer end to a bracket 109 secured to the outer end of the rack mounting plate 104.

15 It will be readily apparent that extension and retraction of the piston rod 108 will cause longitudinal movement of the rack 103 to effect rotation of pinion 102, shaft 99 and driving pinion 98 which will in turn cause the rollover device B to be rotated about its axis. A bellows type cover 111 surrounds the piston rod 108 of the fluid motor 107 to prevent dust or extraneous material from entering the fluid motor.

As illustrated in Figs. 2 and 9, a switch operating cam 112 is mounted on the bottom of the plate 104 and extends laterally into alignment with the operating levers 113 of limit switches B1, B2, B3 and B4. As illustrated in Fig. 2, the fluid motor 88 for operating the clamping plates 76 has mounted thereon a bracket arm 114 which extends into parallel relationship with the path of movement of the piston rod 86. Mounted on the outer end portion of the bracket arm 114 are limit switches B5 and B6. The operating arms of the limit switches B5 and B6 are arranged in the path of travel of the switch operating cam 115 mounted on the piston rod 86 of the fluid motor 88.

30 35 The arrangement and operation of limit switches B1 to B6, inclusive, for controlling the operation of the rollover device B, will be described at a later point.

Referring now to Figs. 1 and 2 for a detail description of the transfer device C, it will be noted that this device 40 includes a double acting fluid motor 116 which is mounted on a suitable supporting structure 117 with its axis in a plane that is normal to the axis of the rollover device B. The axis of the fluid motor 116 is also in alignment with the openings that are formed between the plates 73 of the 45 rollover device B when the clamping plates 76 are in their horizontal positions. The manner in which the fluid motor 116 is mounted on its supporting structure 117 is identical to the mounting of the fluid motor 44 of the transfer device A on its supporting structure 39 and will 50 not again be described, the same reference characters having been assigned to the corresponding portions of the two mounting structures. It will be noted, however, that the switch operating cam 118 associated with the fluid motor 116 is shorter than the cam 59 and that a single 55 limit switch C1 is mounted on the switch mounting bracket 119 at the outer end of the supporting structure 117 and a single limit switch C2 is mounted on the bracket 121 at the inner end of the supporting structure. The manner in which the limit switches C1 and C2 control the operation 60 of the fluid motor 116 will be fully explained at a later point in the specification.

As illustrated in Figs. 5, 6, and 11 to 14, the shakeout device D includes a support 122 that is rigidly connected to the support 61 of the rollover device B. Loosely 65 suspended from the support 122 by bolts 123 is a side plate 124 the inner surface of which is in alignment with the inner surface of the end plate 68 of the rollover device B. Loosely suspended from the support 122 at the opposite side of the shakeout device B is an adjustable 70 side plate 125 which is laterally movable relative to the side plate 124 and which is supported by bolts 126 which are movable in the slots 127 of the supporting structure, as best illustrated by broken-lines in Fig. 13. Each of the side plates 124 and 125 is provided with a flask supporting ledge 128 the top of which is substantially aligned 75

with the bottom of the opening formed between the members 73 of the rollover device B, as best illustrated in Fig. 6.

Referring now to Figs. 5 and 11 to 14, inclusive, for a detail description of the side plates 124 and 125 and the mechanism for adjusting the lateral position of the side plate 125, it will be noted that these plates are of identical construction so that the following description of the side plate 124 will be applicable to both. An outwardly projecting mounting flange 129 is provided at the top of the side plate 124 and is suitably reinforced by webs 131 to receive the mounting bolts 123 by means of which the side plate is suspended from the supporting structure 122. Each bolt 123 is provided with flexible washers 132 adjacent the supporting structure 122 to permit limited vertical movement of the side plate 124 as will be later described. Positioned beneath the mounting flange 129 on the outer side of the plate 124 is a bracket 133 upon which is mounted a conventional type pneumatic vibrator 134 which imparts vibratory vertical movement to the side plate 124 by means of a rapidly reciprocated piston, not shown.

Mounted on the outer side at each end portion of the side plate 124 are two vertically arranged guide brackets 135 and 136 providing vertically extending, opposed grooves for receiving the opposite edge portions of a guide plate 137 that is rigidly connected to the supporting structure by struts 138. The guide plates 137 are vertically movable relative to the associated grooves provided by the brackets 135 and 136 to permit vertical movement of the side plate 124 while limiting its lateral movement.

The guide plates 137 associated with the side plate 125 are mounted on struts 139 having slots 141 therein as illustrated in Fig. 11. Bolts 142 extend through the slots 141 for connecting the struts 139 to the supporting structure 122 in such a manner that loosening of the bolts will permit lateral movement of the struts on the supporting structure. As best illustrated in Figs. 11, 12 and 14, the struts 139 are moved relative to the supporting structure 122 by means of connectors 143 which are threaded through nuts 144 mounted on the supporting structure. The inner ends of the connectors 143 are fastened to the guide plates 137 by brackets 145 which permit rotation of the connectors relative to the plates for adjusting the lateral spacing between the side plates 124 and 125.

Proper adjustment of the threaded connectors 143 will effect and maintain proper spacing between the side plates 124 and 125 so that the side plates will engage the lugs 33 at the sides of their associated flasks 28 to prevent lateral movement of the flasks in the shakeout device D. The ends of the side plates 124 and 125 adjacent the rollover device B are flared outwardly to guide the movement of successive flasks 28 into the shakeout device D.

As each successive flask 28 is pushed out of the rollover device B and into the shakeout device D by the transfer device C, the preceding emptied flask will be ejected from the shakeout device by the incoming loaded flask. The emptied flasks 28 leaving the shakeout device D move onto the rollers 35 for successive engagement by a stop 146, which will limit movement of the flask on the rolls 35 to properly position the succeeding flask in the shakeout device, and a pusher 147 which will move the flask laterally off of the rolls 35 onto the gravity type conveyor 36. The stop 146 is adjustable toward and away from the shakeout device D so that flasks of various lengths may be accommodated on the rolls 35 and will properly index the succeeding flask in the shakeout device D. The stop 146 and pusher 147 are mounted on a supporting structure 148, which is formed of suitably arranged structural members, and together make up the transfer device E.

Referring now to Figs. 15 to 21, inclusive, for a detail description of the transfer device E, it will be noted that the stop 146 is formed of two spaced side plates 149 and

a front plate 151 which extends between the two side plates and along the initial portion of the gravity conveyor 36. Each of the side plates 149 is provided with elongated mounting slots 152 for receiving bolts 153 which adjustably connect the side plates to the supporting structure 148. Mounted at both the top and bottom, at the inner end portion, of each side plate 149 are the brackets 154 to which are rotatably connected the inner ends of adjusting bolts 155 which are threaded through nuts 156 mounted on the supporting structure 148 so that rotation of the bolts 155 will cause the side plates to be advanced or retracted toward or away from, respectively, the shakeout device D.

Mounted in a suitable opening in the front plate 151, by means of hinges 157, is a door 158 that is aligned with the shakeout device D for engagement by the emptied flasks 28 ejected from the shakeout device to effect closing of the door. As is best illustrated in Fig. 19, the door 158 is urged toward its open position by a spring 159 which is stretched between and connected to one of the side plates 149 and an operating arm 161 that is mounted on the door. As illustrated in Fig. 21, the door 158 is also provided with a detent 162 for engaging the inner surface of the front plate 151 to limit opening movement of the door. A limit switch E3 is mounted on the inner side of the front plate 151 with its operating arm 163 continuously engaging the door 158 so that movement of the latter between its open and closed positions will effect actuation of the limit switch. The function of the limit switch E3 in controlling operation of the transfer device E will be fully described at a later point.

The pusher 147 of the transfer device E is formed with a plate 164 that is suspended for movement along and above the rolls 35 by a channel shaped vertical member 165 having connected to its upper end portion two horizontally arranged angle members 166 which are confined between vertically spaced guide members 167 and rest upon bearing plates 168. An inverted channel member 169 is positioned between and connected to the outer end portions of the angle members 166 to maintain proper spacing of the angle members as they are moved along the bearing plates 168 to move the pusher plate 164 across the rollers 35.

Movement of the pusher plate 164 is effected by a double acting fluid motor 171 which is mounted beneath the channel member 169 and has its piston rod 172 connected to the vertical channel 165. The piston rod 172 is provided with a bellows cover 173 to prevent foreign matter from collecting on the rod and thus entering the fluid motor 171.

Mounted on the upper surface of the channel member 169 is a switch operating cam 174 which is movable with the channel member to engage the operating arms 175 of limit switches E1 and E2 as the pusher plate 164 is moved into its extended and retracted positions. The function of the limit switches E1 and E2 in controlling operation of the device E will be fully described at a later point.

Referring once again to Fig. 1, it will be noted that a control bridge F is positioned alongside the mold conveyor 25 where it approaches and departs from the transfer device A. The control bridge F includes a guide bar 176 which is arranged in horizontal alignment with the bottom portion of the mold flasks 28 as they approach the transfer device A and converges gradually toward the conveyor 25 to ensure proper alignment of the flasks 28 on the conveyor trays 26 and to prevent accidental engagement between the flasks and the supporting structure 39 of the transfer device A. The remainder of the control bridge F provides a support 177 which is formed of suitable structural members and upon which are mounted limit switches F1, F2, F3, F4 and F5. The limit switches F2, F3 and F4 are arranged on the supporting structure 177 for successive engagement of their operating arms 178 by the switch operating cams 27 on the

trays 26 of the mold conveyor 25. Mounted on the approach end portion of the supporting structure 177 is a detector arm 179 which is pivotally mounted and is urged into the path of movement of the flasks 28 by a spring 181. The detector arm 179 has mounted on the back thereof a switch operating lug 182 which is movable to engage and actuate the operating arm 178 of the limit switch F1 as the detector arm swings into and out of the path of movement of the flasks 28. Mounted on the opposite end portion of the supporting structure 177 is a similar detector arm 183 which is urged into its normal position overlying the trays 26 of the mold conveyor 25 by a spring 184. The detector arm 183 is also provided with a switch operating lug 185 on the back thereof which is movable into engagement with the operating arm 178 of the limit switch F5 by movement of a flask 28 past the transfer device A.

Operation of the fluid motor 44 of the transfer device A, the fluid motors 88 and 107 of the rollover device B, the fluid motor 116 of the transfer device C and the fluid motor 171 of the transfer device E is each separately controlled by a conventional four-way valve. Each of these valves is moved between its two operative positions for alternately admitting pressure fluid to opposite ends of its associated motor while exhausting the fluid from the other end of the motor by the momentary flow of current through one or another of two solenoids which are associated with the valve. If both of the solenoids are de-energized, the valve will remain in the position to which it was moved by the last energized solenoid.

Reference now will be made to the wiring diagram of Fig. 23 for an understanding of the various control circuits for the valves of the different fluid motors. A valve V-44, of the above mentioned type, is associated with the fluid motor 44 and the coils of the two operating solenoids for this valve are labeled "Push" and "Return" to indicate the direction of movement of the fluid motor effected by momentary energization of one or another of the coils. Valves V-118 and V-171 are associated with the fluid motors 116 and 171, respectively, and are similarly labeled. A valve V-88 is associated with the fluid motor 88 and has the coils of its operating solenoids labeled "Clamp" and "Unclamp" to indicate the direction of movement of the clamping plates 76 of the rollover device B when one or another of the coils is energized. A similar valve V-107 is associated with the fluid motor 107 and is illustrated with the coils of its operating solenoids labeled "Left" and "Right" to indicate the direction of movement, as viewed in Figs. 1 and 2, of the rack 103 associated with the fluid motor for effecting the 180° rotation of the rollover device B in alternate directions.

There is also diagrammatically illustrated in Fig. 23 an emergency relay having an operating coil ER and four magnetically operated contactors ER-1, ER-2, ER-3 and ER-4, which are closed by energization of the coil ER. Latching relays LR1, LR2 and LR3, diagrammatically illustrated in Fig. 23, are each of the type in which a contactor or switch is electrically operated by the momentary energization by an electro-magnet coil and is held in the position to which it is moved by a mechanical latch. A second coil is provided which releases the mechanical latch and permits the contactor to drop into the opposite position under the influence of gravity or by spring action. When both coils are de-energized, the contactor may be in either position depending upon which of the two coils was last energized. The coils of each latching relay LR1, LR2 and LR3 are labeled L and U to facilitate an understanding of the movement of the contactors controlled by the latching relays.

Latching relay LR1 includes a contactor LR11 and a contactor LR12 the former of which is closed and the latter of which is opened by energization of the coil U of this latching relay. A subsequent de-energization of the coil U and energization of the coil L will cause the

positions of the two contactors LR-11 and LR-12 to be reversed. It will be readily apparent, therefore, that as illustrated in Fig. 23, the latching relay LR1 is in its unlatched position. In other words, the coil U of the relay LR1 is the last one to have been energized.

Latching relay LR2 is provided with four contactors LR21, LR22, LR23 and LR24 the first and third of which are caused to close by energization of the coil U of the relay and the second and fourth of which are caused to open by energization of the coil U. De-energization of the coil U and subsequent energization of the coil L of the latching relay LR2 will cause a reversal in the above described positions of the contactors LR21, LR22, LR23 and LR24 and it will be readily apparent by reference to Fig. 23 that the latching relay LR2 is illustrated as being in its latched position.

Latching relay LR3 includes the single contactor LR31 which is opened by energization of the coil U of this relay and is closed by subsequent de-energization of the coil U and energization of the coil L. It will be readily apparent, therefore, that the latching relay LR3 is illustrated in Fig. 23 as being in its unlatched position.

The control circuit diagrammatically illustrated in Fig. 23, in addition to the above described elements, includes the starting relay M for the mold conveyor 25 which, in addition to controlling operation of the mold conveyor, operates a contactor M1 in the control circuit. A circuit breaker OL is also provided in series with the starter relay M for interrupting the circuit through the starter relay if an overload occurs in the circuit and an additional contactor S, closed by energization by the starter relay of the screen 37, not shown, provides an interlock between the conveyor starter circuit and the screen circuit to prevent operation of the mold conveyor unless the screen is first set into operation.

Referring now to Figs. 22 and 23 for a detail description of the operation of the machine illustrated in Fig. 22 and the manner in which its operation is controlled, the vibrators 134 and shakeout screen 37 are first set in operation and will continue throughout the period of operation of the rollover and shakeout devices. The mold conveyor 25 is thereafter set in operation by actuating the starter button 186 and the reset button 187 in the control circuit. Actuation of the reset button will permit current to flow between electrical supply lines L1 and L2 through the coil ER of the emergency relay to close the contactors ER1, ER2, ER3 and ER4 of the emergency relay. The contactor ER1 is arranged in parallel with the reset button 187 so that subsequent release of the button will not interrupt the current through the coil ER. The contactors ER3 and ER4 are positioned in lines L1 and L2 to control the supply of current to the separate parallel branches of the control circuit in which are positioned the valves V44, V88, V107 and V116 and the latching relays LR1, LR2 and LR3.

After the reset button 187 has been actuated to close the contactor ER2, the circuit between lines L1 and L2 through the coil M of the mold conveyor starter relay is completed through the normally closed circuit breaker OL, the coil M, the starter button 186, the normally closed stop buttons 188, the contactor S, which is interlocked with the shakeout screen starter relay, the contactor ER2, normally closed limit switch F5, through the contact LR11 of latching relay LR1, or the normally closed limit switch F4 which are arranged in parallel relationship and through the normally open limit switch A1 or the normally closed limit switch F3 which are also arranged in parallel relationship.

The limit switch F5 is normally closed, that is it is closed when the actuating arm of the switch is not engaged and moved by its associated switch operating lug 185. This limit switch, therefore, will never interrupt the flow of current through the mold conveyor starter unless a mold flask 28 for some reason passes the transfer device A. The limit switch F3 is also normally closed but is

opened just prior to the movement of a mold flask 28 into alignment with the transfer device A by engagement with one of the switch operating cams 27 on the trays 26 of the conveyor 25 so that the conveyor will be stopped if the fluid motor 44 has not been retracted for a sufficient distance to clear the oncoming flask and to cause the switch operating cam 59 to close the normally open limit switch A1. If the switch operating cam 59 has not returned to the above mentioned position at which the limit switch A1 is closed, opening of the limit switch F3 will interrupt the circuit through the mold conveyor starter relay coil M and will cause the mold conveyor to stop. Limit switch F4 is normally closed but is opened by engagement with one of the operating cams 27 just prior to movement of a flask 28 into alignment with the transfer device A and will interrupt the circuit through the mold conveyor starter coil M to stop the mold conveyor 25 if the contactor LR11 has not been closed by movement of the fluid motor 116 to clear the preceding flask from the rollover device B. Movement of the fluid motor 116 to clear the rollover device B will actuate the limit switch C2 to energize the coils U of the latching relays LR1 and LR3 and close the contactor LR11 as will be more fully described at a later point.

As a mold flask 28 is moved by the conveyor 25 into alignment with the transfer device A, the detector arm 179 is deflected by the flask to cause the switch operating lug 182 to engage and close the normally open limit switch F1. If for any reason, however, there is no flask 28 on the tray 26 approaching the transfer device A, the detector arm 179 will not be deflected and the limit switch F1 will remain open so that the operation of the rollover and shakeout devices will not be started.

Limit switch F2 is operated by the cam 27 on the side of a tray 26 of the mold conveyor as it moves into alignment with the transfer device A to close the normally open limit switch F2. If the fluid motor 116 has returned to its fully retracted position to close the normally open limit switch C1, the closing of the limit switch F2 will complete a circuit between lines L1 and L2 through the "Push" solenoid of valve V44 and limit switches C1, F1 and F2 to cause the fluid motor 44 to engage and move the aligned flask 28 off of the conveyor 25 and across the rollers 34 into the rollover device B. If, however, the fluid motor 116 has not returned to its retracted position to close the normally open limit switch C1, the circuit through the "Push" solenoid of the valve V44 will remain open and the fluid motor 44 will not operate.

The fluid motor 44 is adjusted on its supporting structure 39 by means of the hand wheel 49 to a position at which the flask 28 will be seated against the end plate 63 of the rollover device B when the fluid motor 44 is in its fully extended position. As the fluid motor 44 nears the end of its pushing stroke, normally closed limit switch A3 is opened by engagement of the switch operating cam 59 to prevent actuation of the fluid motor 107 until the fluid motor 44 has cleared the rollover device B on its return stroke. Normally open limit switch A2 closes at the end of the "Push" stroke of the fluid motor 44 to close the branch circuit between lines L1 and L2 through the "Return" solenoid of the valve V44, the "Push" solenoid of the valve having been previously de-energized by movement of the switch operating lug 27 of the conveyor to permit opening of the limit switch F2. The momentary closing of the normally open limit switch A2, therefore, actuates the valve V44 to cause the fluid motor 44 to return to its retracted position.

Momentary closing of the limit switch A2 also closes the branch circuits through the coil L of latching relay LR1 and the "Clamp" solenoid of valve V88 to thereby open the contactor LR11 and close the contactor LR12 of latching relay LR1 and to start operation of the fluid motor 88 to effect clamping of the flask 28 in the rollover device B.

When the fluid motor 88 is set in operation to clamp the

flask 28 in the rollover device B, the normally open limit switch B6 operates to open the branch circuits through the latching relay LR2 and the "Push" solenoid of valve V116 so that the latching relay cannot be energized and the valve cannot be actuated to effect movement of the fluid motor 116 toward the rollover device B. When the fluid motor 88 has fully clamped the flask 28 in the rollover device B, the normally open limit switch B5 is closed to complete the branch circuit through the "Left" solenoid of valve V107. Before the "Left" solenoid of the valve V107 can be energized, however, it is necessary that the fluid motor 44 be sufficiently retracted on its return stroke to effect closing of the normally closed limit switch A3.

The limit switch B5 is adjustably mounted on the bracket 114 to permit vertical movement thereof so that flasks 28 of different heights may be clamped in the rollover device B at the time that the limit switch B5 is closed.

It is presumed for the purpose of this description that the fluid motor 107 is initially in its extended position so that the limit switch B2 is closed by the switch operating cam 122 and movement of the rack 103 will be from right to left as viewed in Fig. 1. The limit switch B4 will also be closed and energization of the coil L of latching relay LR2 would have caused opening of the contactors LR21 and LR23 and closing of the contactors LR22 and LR24 of the latching relay LR2. If, however, the preceding stroke of the fluid motor 107 was to the left, limit switches B1 and B3 would have been closed by engagement with the operating cam 112 and limit switches B2 and B4 would be in their normally open positions. Also, the coil U of latching relay LR2 would have been the last energized coil in the relay so that contactors LR21 and LR23 would have been closed and contactors LR22 and LR24 would have been open. Closing of the limit switch B5, therefore, will alternately energize the "Left" and "Right" solenoids of the valve V107 on successive strokes of the fluid motor 107.

Each stroke of the motor 107 will cause rotation of the rollover device B through 180° to invert the flask 28 on each successive cycle of operation of the device. Further, the rotation of the rollover device B will move the follower 95 associated with the initially lower clamping plate 76 into engagement with a cam plate 96 to lower the clamped flask 28 to a position at which the new lower plate 76 is aligned with the plates 73 and the support flanges 128 of the shakeout device D.

After the fluid motor 107 has effected a 180° rotation of the rollover device B, limit switch B1 or B2, depending upon the direction of the rotation of the rollover device is closed to complete a circuit through the contactor LR24 or LR21, respectively, and the "Unclamp" solenoid of the valve V88. The closing of either limit switch B1 or B2 also energizes the coil L of latching relay LR3 by closing the branch circuit through contactor LR24 or LR21 to close the contactor LR31 in the circuit of the "Push" solenoid of valve V116.

After the fluid motor 88 is set in operation by energization of the "Unclamp" solenoid of the valve V88 and starts to unclamp the flask 28 in the rollover device B, the normally open limit switch B5 opens to break the circuits through both solenoids of the valve V107 and to thereby positively prevent the fluid motor 107 from operating until the next cycle. When the fluid motor 88 reaches its fully unclamped position the normally open limit switch B6 is closed to complete the branch circuit through the closed limit switch B3 and the coil U of latching relay LR2 so that the contactors LR21, LR22, LR23 and LR24 have their positions reversed for the next movement of the fluid motor 107 from left to right as described above. Also, the closing of the limit switch B6 completes the circuit through the limit switch E1 and the contactor LR31 of latching relay LR3 to energize the "Push" solenoid of the valve V116, the limit switch E1 having been previously closed by

movement of the fluid motor 171 into its fully retracted position at which the operating cam 175 engages and closes the limit switch E1.

Energization of the "Push" solenoid of the valve V116 will cause the fluid motor 116 to be set in operation to push the flask 28 out of the rollover device B and into the shakeout device D where the sand and casting of the inverted flask are shaken out and will fall onto the vibrating screen 37. As the fluid motor 116 starts its push stroke, limit switch C1 opens to break the branch circuits through the "Push" solenoids of both of the valves V44 and V171. At the end of its push stroke, the switch operating cam 118 of the fluid motor 116 engages and closes limit switch C2 to close the branch circuits through the "Return" solenoid of valve V116 and coils U of latching relays LR1 and LR3. Energization of the "Return" coil of valve V116 will reverse the direction of movement of the fluid motor 116 to cause its movement into its fully retracted position. The contact LR31 operated by the latching relay LR3 is opened by energization of the coil U of the relay to prevent the fluid motor 116 from operating again until the next cycle of the device. Contactor LR11 of the latching relay LR1 is closed and contactor LR12 is opened by energization of the coil U of latching relay LR1. Opening of limit switch F4, therefore, will not stop the operation of the mold conveyor 25 as would be the case if the flask 28 had not been cleared from the rollover device B. Opening of the contactor LR12 breaks the circuits through the "Left" and "Right" coils of the valve V107 to positively prevent any operation of the rollover device B until the next cycle.

When the flask 28 in the rollover device B is pushed into the shakeout device D by the fluid motor 116, the preceding flask 28, which was previously pushed into the shakeout device, is pushed by the incoming flask to a position where it is supported by the rolls 35 in line with the gravity conveyor 36. The fluid motor 116 is adjusted by means of its handwheel 49 and the stop plate 151 is adjusted on its support 148 so that the ejected flask 28 will engage the stop plate when the motor 116 reaches the end of its push stroke and the flask has fully cleared the shakeout device D. The outer end of the ejected flask 28, therefore, will engage the door 158 to move it into its closed position and to close the normally open limit switch E3. This closing of the limit switch E3 completes the branch circuit through the "Push" solenoid of valve V171 so that the fluid motor 171 is set in operation to push the flask 28 laterally from the rolls 35 onto the gravity conveyor 36. Before the circuit through the closed limit switch E3 can be completed, however, it is necessary that the fluid motor 116 be fully returned to its retracted position to close the normally open limit switch C1.

As the fluid motor 171 moves forward on its push stroke, limit switch E1 is opened to break the branch circuit through the "Push" solenoid of valve V116 and positively prevent energization of the valve until the fluid motor 171 has returned to its fully retracted position. At the end of its push stroke the fluid motor 171 will move its switch operating cam 175 into a position to close the normally open limit switch E2 and to thereby close the branch circuit through the "Return" solenoid of valve V171. The "Push" solenoid of valve V171 will have been previously de-energized by movement of the flask 28 off of the rolls 35 to permit the door 158 to return to its open position and to thereby open the limit switch E3. When the "Return" solenoid of the valve V171 is energized, the fluid motor 171 will return to its fully retracted position at which time the limit switch E1 is again closed.

All of the above described control operations are repeated for each cycle of the machine, the fluid motor 107 being operated in opposite directions during succeeding cycles of the device. In case of a power failure at any time during a cycle, the operation will stop at the point

of interruption except that any fluid motors which are in motion will continue until they reach the ends of their strokes. When power is again available, resetting of the emergency relay ER and actuation of the starter button 5 186 will continue the cycle from the point of interruption.

In order to prevent interruption of the continuous movement of the mold conveyor 25 and to provide for a continuous flow of mold flasks 28 through the rollover and shakeout devices, the above described operations of a 10 single cycle are in some instances overlapped. In other words, certain of the operations are started before the preceding operations have been completed, the timed relationship between the various operations in a single cycle being best illustrated in Fig. 24 where each movement of 15 the fluid motors 44, 88, 107, 116 and 171 is plotted through a cycle of 12 seconds.

Referring now to Fig. 24 for a detail description of the time relationship of the operation of each fluid motor during a given 12-second cycle, it will first be noted that 20 the vibrators 134 and mold conveyor 25 operate continuously throughout the cycle. At the beginning of the cycle, the fluid motor 44 moves into its forward or push stroke which continues for 2.5 seconds. It will be noted that the return stroke of the fluid motor 171 in the preceding cycle ends at .05 second after the beginning of 25 the forward stroke of the fluid motor 44. At the end of the forward stroke of the fluid motor 44 the fluid motor 88 begins its clamping movement and the fluid motor 44 begins its return movement. The clamping movement 30 of the fluid motor 88 requires .26 second and at .42 second after the beginning of the clamping movement of the motor 88, the fluid motor 107 is set in operation to effect 180° rotation of the rollover device B. Before the fluid motor 107 is set in operation, however, the fluid motor 35 44 will have travelled 15 inches in its return stroke so as to clear the rollover device B before the fluid motor 107 is set in operation. At the end of 1.8 seconds the return stroke of the fluid motor 44 is completed and the fluid motor 107 continues to operate for a total elapsed time 40 of 2.75 seconds. At the end of this period the fluid motor 107 will have completed its rotation of the rollover device B and the fluid motor 88 is once again set in operation to release or unclamp the flask 28 in the rollover device. This unclamping operation of the fluid motor 88 requires a period of .26 second and immediately at the 45 end of this period the fluid motor 116 is set in operation and will move through its forward stroke in 2.5 seconds and its return stroke in 1.67 seconds. Immediately upon the completion of the return stroke of the fluid motor 116, the fluid motor 171 is set in operation and will complete 50 its forward stroke in 1.17 seconds and its return stroke in .78 second so that the return stroke is completed .05 second after the end of the 12-second cycle period and the fluid motor 44 will have begun its forward stroke for the 55 next cycle before the return stroke of the fluid motor 171 has been fully completed.

It will be noted that the mold conveyor 25 will travel 23 inches after the beginning of the cycle before the largest flask 28 carried by the conveyor could strike the 60 piston rod 52 of the fluid motor 44 and that during the 6.25-second period which is required for this amount of travel of the conveyor, the fluid motor 44 will have had ample time to complete its forward and return strokes so that no flasks 28 will be permitted to collide with the 65 piston rod during the return stroke of the motor 44.

It will be appreciated from the above description of the operation and control of the rollover and shakeout devices that the loaded mold flasks 28 will be removed from the conveyor 25, inverted, and the contents shaken 70 therefrom completely automatically and without interruption of the operation of the mold conveyor.

It is to be understood that the form of this invention herewith shown and described is to be taken as the preferred example of the same, and that various changes in 75 the shape, size, and arrangement of parts may be resorted

to without departing from the spirit of the invention or the scope of the subjoined claims.

Having thus described the invention, I claim:

1. Foundry equipment of the type described, comprising a conveyor for successively moving mold flasks into a shakeout location, mold flask inverting means positioned adjacent said shakeout location, means actuated in response to movement of a mold flask by said conveyor into said shakeout location for transferring the flask from said conveyor into said inverting means, means responsive to the movement of a flask into said inverting means for clamping the flask therein, means responsive to the clamping of a flask in said inverting means for actuating the latter to invert the flask, said clamping means being movable to release the flask in response to the complete inversion of the latter, means for receiving and vibrating the inverted flask to remove the contents therefrom, and means responsive to the release of the flask by said clamping means for transferring the inverted flask from said inverting means into said vibrating means.

2. Foundry equipment as specified in claim 1 further characterized by means adjacent said vibrating means for receiving the inverted flasks that are ejected from the vibrating means by the transfer of successive flasks thereto, a conveyor for returning the ejected flasks to a point of reuse, and means responsive to the ejection of a flask from said vibrating means for transferring the ejected flask from said receiving means to said flask returning conveyor.

3. Foundry equipment as specified in claim 1 further characterized by means for stopping said conveyor in response to movement of a flask thereby past said shakeout location, and means for preventing actuation of the means for transferring a flask from said conveyor to said flask inverting means until the preceding flask is transferred from the inverting means to said vibrating means.

4. Foundry equipment as specified in claim 1 further characterized by said flask clamping means having vertically spaced clamping members mounted on said flask inverting means for movement relative to each other to clamp the flask therebetween, the top and bottom positions of the members being reversed by the inversion of the flask, and said members being jointly movable in their flask clamping positions to align the inverted flask with the vibrating means for transfer to the latter.

5. Foundry equipment as specified in claim 1 further characterized by means for engaging said clamping means to move the clamping means and the associated clamped flask relative to the inverting means during inversion of the flask, said relative movement of the clamping means returning the inverted flask to its original elevation for transfer to the vibrating means and positioning said clamping means for receiving the succeeding flask.

6. Foundry equipment as specified in claim 1 further characterized by said flask clamping means having vertically spaced clamping members mounted on said flask inverting means for movement relative to each other to clamp a flask therebetween, a follower mounted on each of said clamping members, and camming means for engaging the follower of the initially lower clamping members to jointly move the clamping members and the associated clamped flask relative to the inverting means during inversion of the flask, said relative movement of the clamping members positioning the initially upper member at the original elevation of the initially lower member.

7. Foundry equipment as specified in claim 1 further characterized by said vibrating means having laterally spaced, resiliently supported members between which the inverted flask is received, laterally opposed flanges on said spaced members for engaging the lower edge at each side of the flask to support the latter, and a vibrator mounted on each of said spaced members for imparting vibratory movement to the spaced members and their flanges and to the associated flask, said vibratory movement causing the contents of the flask to fall through the inverted top thereof.

8. Foundry equipment as specified in claim 1 further characterized by said flask inverting means being rotatable about a substantially horizontal axis and having diametrically opposed openings which are alternately positioned in alignment with and adjacent to the vibrating means by actuation of the inverting means to invert successive flasks, said flasks being transferred from said inverting means to the vibrating means through the opening adjacent the latter.

9. Foundry equipment as specified in claim 1 further characterized by said flask inverting means being mounted for rotation about an axis substantially normal to the direction of movement of said flasks by said conveyor, said inverting means having an end opening through which successive flasks are transferred into the inverting means and two diametrically opposed lateral openings through alternate ones of which successive flasks are transferred from the inverting means into the vibrating means, and said clamping means having clamping members movable radially inwardly from alignment with the tops and bottoms of said openings to support the flasks during the inversion thereof.

10. Foundry equipment as specified in claim 1 further characterized by said conveyor being adapted to be continuously operated, said first mentioned flask transferring means effecting transfer of successive flasks from the moving conveyor to said flask inverting and clamping means, the means for actuating the inverting means and the last mentioned transferring means being operated in timed relationship to clear each inverted flask from the inverting means before the next succeeding flask is transferred thereto.

11. Foundry equipment of the type described, comprising a conveyor for successively moving mold flasks into a shakeout location, mold flask inverting means positioned adjacent said conveyor at said shakeout location, a first fluid motor positioned adjacent said conveyor at said shakeout location and actuated in response to movement of a flask by said conveyor into said shakeout location for transferring the flask from the conveyor into the inverting means, means responsive to the movement of a flask into said inverting means for clamping the flask therein, means responsive to the clamping of a flask in said inverting means for actuating the latter to invert the flask, said clamping means being movable to release the flask in response to complete inversion of the latter, means for receiving and vibrating the inverted flask to remove the contents therefrom, and a second fluid motor positioned adjacent said inverting means and actuated in response to the release of the flask by said clamping means for transferring the inverted flask from said inverting means into said vibrating means.

12. Foundry equipment as specified in claim 11 further characterized by said first fluid motor being adjustably mounted for bodily movement relative to said flask inverting means to properly positioned flasks of different widths in the inverting means, and said second fluid motor being adjustably mounted for bodily movement relative to the flask inverting means to properly position flasks of different lengths in said vibrating means.

13. Foundry equipment as specified in claim 11 further characterized by support means adjacent said vibrating means for receiving the inverted flasks that are ejected from said vibrating means by the transfer of successive flasks thereto, a stop associated with said support means and adjustable relative thereto to limit the movement of the ejected flasks and their succeeding flasks and to thereby properly position flasks of various lengths in the vibrating means, a conveyor for returning the ejected flasks to a point of reuse, and a third fluid motor positioned adjacent the support means and actuated in response to movement of an ejected flask into engagement with said stop for transferring the ejected flask from said receiving means to said flask returning conveyor.

14. Foundry equipment as specified in claim 13 further

characterized by each of the three fluid motors being arranged to transfer the flask associated therewith by movement into an extended position, a separate valve for controlling the actuation of each of said fluid motors, the valves associated with said first and third motors being operable to effect movement of their associated motors into their extended positions only when the second fluid motor is in its retracted position, and the valve associated with said second fluid motor being operable to effect movement of its associated motor into its extended position only after the flask in said inverting means has been inverted and unclamped and the third fluid motor is in its retracted position.

15. Foundry equipment as specified in claim 14 further characterized by means associated with each of said fluid motors and actuated by movement of the motors into their extended positions to cause operation of the associated valves to effect return of the motors to their retracted positions, and means for stopping said conveyor to prevent movement of a flask thereby into said shakeout location unless said first fluid motor is returned to its retracted position and said second fluid motor has actuated the means for effecting return thereof to its retracted position.

16. Foundry equipment of the type described, comprising a conveyor for successively moving mold flasks into a shakeout location, a flask inverting device mounted for rotation about a substantially horizontal axis and having an end opening adjacent said conveyor at said shakeout location and two diametrically opposed side openings, a first fluid motor mounted on the opposite side of said conveyor from said end opening and actuated by movement of a flask into said shakeout location for movement into an extended position to transfer the flask into said inverting device through said end opening, a pair of spaced clamping plates mounted on said inverting device for movement into clamping engagement with the top and bottom of the flask in response to transfer thereof into the inverting device, a second fluid motor responsive to the clamping of the flask for rotating the inverting device through one-half revolution to invert the flask, said clamping plates being moved to release the flask in response to the aforesaid rotation of the inverting device, a laterally spaced pair of substantially vertical vibrator plates resiliently supported adjacent one side of said inverting device, said side openings of the latter being alternately positioned adjacent said vibrator plates by successive rotations of the inverting device, a flange extending inwardly from each vibrator plate in alignment with the bottom of the adjacent side opening, a vibrator mounted on each vibrator plate, and a third fluid motor mounted adjacent the side of said inverting device opposite said vibrator plates and actuated in response to the release of the flask by said clamping plates for movement to an extended position through the adjacent side opening of the inverting device to transfer the flask through the opposite side opening and into a position between said vibrator plates with the bottom edges at each side of the flask resting on said flanges.

17. Foundry equipment as specified in claim 16 further characterized by a support formed of horizontally arranged parallel rollers mounted adjacent the ends of said resiliently supported plates opposite said inverting device and with their tops in alignment with said flanges to receive the flasks that are ejected from between the vibrator plates by the transfer of succeeding flasks thereto, a conveyor extending from adjacent said support for returning the ejected flasks to a point of reuse, and a fourth fluid motor mounted on the opposite side of said support from the adjacent portion of the flask returning conveyor and actuated by movement of an ejected flask to said support for movement into an extended position to transfer the ejected flask from the support to the flask returning conveyor.

18. Foundry equipment as specified in claim 16 further characterized by a pair of clamping levers each having one end portion pivotally connected to the outer surface of an associated one of said clamping plates and a spaced portion pivotally connected to said inverting device, and a fluid motor positioned between and pivotally connected to said levers at point that are spaced from their connections to the clamping plates and the inverting device for effecting relative movement of the clamping plates to clamp and release the flask therebetween, said levers being jointly movable to permit movement of the clamping plates in clamped relation with the associated flask.

19. Foundry equipment as specified in claim 18 further characterized by a stop for limiting the outward movement of each of said clamping plates, the lower clamping plate being urged into engagement with its stop by the weight of the flask thereon and the upper clamping plate being moved relative to the lower clamping plate for clamping and unclamping the associated flask, said clamping plates being jointly movable in clamped relationship with said flask between positions at which the clamping plates are engaged by their respective stops.

20. Foundry equipment as specified in claim 19 further characterized by a follower mounted on the outer surface of each clamping plate, and a cam extending along the path of movement of said followers when the inverting device is rotated, the follower of the lower clamping plate engaging the cam during rotation of the inverting device to cause the originally upper plate to be moved into engagement with its stop while the flask is being inverted by the rotation of the inverting device.
